[57] CLAIM

The ornamental design for a pull for drawers or doors, as shown and described.

DESCRIPTION

FIG. 1 is a perspective view of a pull for drawers or doors showing my new design, the broken line showing a portion of a drawer or door for illustrative purposes only;

FIG. 2 is a front elevational view thereof, again with the broken lines for illustrative purposes only;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

FIG. 1
